UNITED STATES PATENT OFFICE

WILLIAM J. MORSE, OF ATTLEBORO, MASSACHUSETTS

BELT BUCKLE

Application filed July 24, 1930. Serial No. 470,325.

This invention relates to an improved construction of belt buckle of the tongue or stud variety employed more particularly for positively retaining the belt in adjusted position about the waist of the wearer.

One object of the invention is to provide such a buckle with a body member having a plate member pivotally attached thereto and to which plate member one end of the belt is attached, one of said members being arranged to carry a tongue or stud member to engage the selected hole in the belt and so positively retain the belt in adjusted position against maximum strains.

15 A further object of the invention is to provide means in one of these members, which are pivotally connected together, for releasably retaining the plate member in operating position between the flanges of the body member.

The invention further consists in the pivoting of one end of the stud-carrying plate member between the flanges of the body member and to offset the free bail-shaped end of 25 the plate member inwardly from the plane of its main part to form this free end in bail shape to which one end of the belt is connected.

With these and other objects in view, the invention consists of certain novel features of construction, as will be more fully described, and particularly pointed out in the appended claim.

In the accompanying drawings:

35 Fig. 1 is a front view showing a portion of a belt to which my improved buckle is attached;

Fig. 2 is a sectional edge view of the belt with my improved buckle attached thereto in closed or operating position;

Fig. 3 shows the body member as having been swung on its plate pivot to withdraw the stud from its hole in the belt;

Fig. 4 is a perspective view of the inner 5 face of the buckle body;

Fig. 5 is a perspective view of the outer face of the stud-carrying link;

Fig. 6 is a section on line 6—6 of Fig. 2, showing the edges of the plate as having been sprung past the protuberances on the flanges

to releasably retain the plate and its stud in its selected hole in the belt;

Fig. 7 is a modification showing a recess formed in the inner face of the buckle body to receive and support the free end of the stud 55 against the strains on the belt;

Fig. 8 is a modification showing the stud as attached to the body to extend and snap thru a hole in the plate.

It is found in the practical use of the clamp 60 type of belt buckles that in some cases they slip on the belt, unless the belt is of exactly the right thickness. To obviate this difficulty, I have provided a buckle which has the advantageous appearance of the clamp buckle 65 but which positively obviates slipping and to which buckle a belt of any thickness may be applied and positively held in any adjusted position. To accomplish this in a simple and effective way, I have provided a buckle 70 having a body member with side flanges between which a stud-carrying plate member is pivotally mounted, the stud being arranged to extend into any selected one of a plurality of holes in the belt to positively retain the 75 belt against slipping.

Then again in my improved construction, by offsetting the belt end of the bail inwardly, the belt serves to assist in holding the stud in engagement with its selected hole in the 80 belt; also I have shown protuberances in the body flanges past which the edges of the plate may be snapped to releasably hold the plate and its stud in belt-engaging position.

Another feature of this invention is that 85 by pulling the free end of the belt outwardly, the body portion thru which this belt end is threaded will swing outwardly on its plate pivot pin and so readily withdraw the stud from its selected belt hole thus releasing the 90 belt from engagement with the buckle permitting adjustment thereof or complete withdrawal from the buckle when desired.

The following is a detailed description of the present embodiment of my invention 95 showing one simple construction of buckle by which these advantageous results may be accomplished:

With reference to the drawings, 10 designates the body of a buckle, which is prefer- 100

ably formed with a plain, front surface plate 11 having rearwardly-extending side flanges 12, one end of these flanges being pierced as 13, while the opposite ends of the flanges 5 are provided with inwardly-extending protuberances 14 for the purpose presently described.

Numeral 15 in the drawings designates the stud plate member of my improved buckle, 10 one end of which is provided with laterally-extending pivots 16 arranged to enter the eyes 13 in the flanges 12 of the body member to hinge the two together. The opposite end of this plate 15 is provided with an opening 17 15 forming a cross bar 18, to perform the function of a bail about which the end 19 of the belt 20 is looped as at 21.

This bail portion is preferably offset rearwardly from the plane of the rest of the plate 20 so that any strain exerted on the belt will serve to assist in holding this plate in closed or belt-engaging position.

On this plate, I have mounted or formed a stud member 22 which may be formed integrally with the plate or secured thereto in any convenient manner that shown being riveted in position. This pin or stud is of a size to enter any selected hole 23 in the end 24 of the belt to positively retain the belt in adjusted 30 position in the buckle.

In order to provide simple, convenient and effective means for releasably securing the plate in operating position with its stud engaging the selected hole in the belt, I have 35 provided the plate of a width so that the edges 25 of the plate 15 will snap under these protuberances 14, see Fig. 6, the resilient side walls 12 yielding by the application of the closing and opening forces to the plate and 40 the body, to cause these side walls to separate and permit the plate to snap by these protuberances.

By my improved construction, it will be seen that in order to release the stud from its 45 selected hole in the belt, it is only necessary to engage the end 24 of the belt and by lifting the same cause the body portion to swing outwardly on the pivot 16 which will withdraw the stud from its selected opening in the 50 belt thus permitting free belt adjustment. In some instances where it is desired to better support the free end of the stud, I have recessed the inner face of the body plate as at 55 26, see Fig. 7, which will support this stud against excessive strains, and in other instances I may attach the stud 27 to the front or body member to extend thru a hole 28 in the plate 29, the pin having an enlargement 60 30 which may be snapped thru the hole 28 in the plate 29.

My improved buckle is very simple and practical in construction and is effective in its operation.

The foregoing description is directed solely towards the construction illustrated, but

I desire it to be understood that I reserve the privilege of resorting to all the mechanical changes to which the device is susceptible, the invention being defined and limited only by the terms of the appended claim.

I claim:

A belt buckle comprising a body member having side flanges, a plate member of sheet stock curved longitudinally and pivotally mounted at one end in said flanges and having a bail at its opposite end offset inwardly from the plane of the plate by a curve of a lesser radius than the curve of said plate to which bail one end of the belt may be connected, a stud carried by said plate member adjacent said bail for engaging a selected hole in the belt, protuberances on said side flanges for extending over the edge of the plate adjacent the bail end for releasably retaining said plate in operating position, said body member being adapted to be swung outwardly on said pivot by lifting the free end of the belt to withdraw the stud from engagement with the belt.

In testimony whereof I affix my signature.

WILLIAM J. MORSE.
